HAND WEIGHT

James H. Edwards, P.O. Box 1081, Evanston, Ill.

Filed Aug. 19, 1964, Ser. No. 81,358

Term of patent 14 years

(Cl. D34—5)

FIG. 1

FIG. 5

FIG. 2

FIG. 3

FIG. 4

FIG. 1 is a perspective view of a hand weight showing my new design;

FIG. 2 is a top view thereof;

FIG. 3 is a front elevation view thereof illustrating a configuration of the front and back thereof;

FIG. 4 is a side elevation view thereof illustrating the configuration of both sides thereof; and

FIG. 5 is a bottom view thereof.

I claim:

The ornamental design for a hand weight, substantially as shown and described.
